VENDING MACHINE

William Clark Makibbin, New Bloomfield, Pa.

Application December 9, 1948, Serial No. 64,285

9 Claims. (Cl. 312—64)

1

My invention relates broadly to vending machines, and more particularly to an improved construction of vending machine especially designed for vending cracker sandwiches either as single units or as grouped package units.

One of the objects of my invention is to provide a practical construction of cracker sandwich vending machine which may be arranged to vend from a turret either as single cracker sandwich units upon insertion of a one cent coin, or arrange to dispense grouped packages of cracker sandwiches upon deposit of coins of larger denomination.

Another object of my invention is to provide a construction of cracker sandwich vending machine in which a multiple rack turret is provided for carrying stacks of cracker sandwiches of different kinds, and wherein a customer may conveniently select the stack from which the kind of sandwich desired may be readily discharged upon actuation of a coin control mechanism.

A still further object of my invention is to provide an arrangement of turret having a multiplicity of storage chutes for receiving and feeding cracker sandwiches of select kinds, with spring retaining means at the bottom of each storage chute for gravitationally receiving and yieldably maintaining a cracker sandwich or a packaged group of cracker sandwiches in a position for selective ejection in accordance with the operation of a coin control mechanism.

Still another object of my invention is to provide an improved construction of ejector mechanism for single cracker sandwiches or packaged group of cracker sandwiches which will selectively effect discharge thereof without breaking, injuring, or disintegrating the sandwich or sandwiches.

Still another object of my invention is to provide an improved form of selective control mechanism for a rotatable turret in a vending machine, for facilitating the movement of the turret to selected positions for operation in conjunction with a coin control mechanism, in combination with means for disabling the coin control mechanism while the turret is being moved to a selected position.

Still another object of my invention is to provide a calibrated dial arrangement and associated merchandise carrying rotary turret mechanism for vending machines for rotatably shifting the turret to a selected discharge position in accordance with the calibrations on the calibrated dial mechanism.

2

Still another object of my invention is to provide a novel arrangement of coin actuating merchandise selector for rotary turret vending machines having means for locking out the coin actuating mechanism for all positions of the rotary turret except selected merchandise delivering positions thereof.

Other and further objects of my invention reside in a practical form of cracker sandwich vending machine as set forth more fully in the specification hereinafter following by reference to the accompanying drawings, in which:

Figure 1 is a vertical sectional view through the vending machine of my invention with parts shown in elevation; Fig. 2 is a front elevational view of the vending machine showing the selector mechanism which is controlled for selecting the different types of merchandise; Fig. 3 is an enlarged fragmentary vertical sectional view showing the arrangement of the selector and ejector mechanism operated by the coin control mechanism according to my invention; Fig. 4 is a transverse sectional view taken substantially on line 4—4 of Fig. 3; Fig. 5 is a transverse sectional view taken substantially on line 5—5 of Fig. 3; Fig. 6 is a fragmentary sectional view of the vending machine with the turret and associated mechanism shown in side elevation; Fig. 7 is an enlarged side elevational view of the ejector mechanism in its initial position preparatory for an ejecting operation; Fig. 8 shows the next succeeding position of the ejector mechanism as the coin controlled mechanism is operated; Fig. 9 illustrates the position of the ejector mechanism upon the completion of the ejection cycle with the merchandise being discharged into the delivery chute; Fig. 10 is a transverse sectional view showing the relation of the parts of the ejector mechanism and the merchandise article retainer adjacent the bottom of the delivery chute just prior to the operation of the ejector mechanism, the view being taken substantially on line 10—10 of Fig. 11; Fig. 11 is a vertical sectional view taken substantially on line 11—11 of Fig. 10; Fig. 12 is a transverse sectional view similar to the view shown in Fig. 10 but illustrating the ejector mechanism in operation for ejecting the merchandise article; Fig. 13 is a fragmentary side elevational view of a modified form of selector mechanism which may be employed in the vending machine of my invention; Fig. 14 is a fragmentary vertical sectional view of the selector mechanism shown in Fig. 13; Fig. 15 is a transverse sectional view taken on line 15—15 of Fig. 13 and showing in top plan view the modified

form of selector mechanism illustrated in Figs. 13 and 14; Fig. 16 is a vertical sectional view of an adaptor that may be inserted in the end of each of the delivery chutes in converting the vending machine from multiple package units to single package units under control of the same ejector mechanism; Fig. 17 is a horizontal sectional view taken on line 17—17 of Fig. 16; Fig. 18 is a front view of the changeable indicator card which may be removably mounted on the front of the vending machine cabinet; and Fig. 19 is a horizontal sectional view taken on line 19—19 of Fig. 18.

Referring to the drawings in detail, reference character 1 designates a base housing for the vending machine of my invention terminating in an annular opening 2 having an annular flange 3 extending therearound and grooved at 4 to receive the cylindrical housing 5. The cylindrical housing 5 is formed from glass or transparent plastic through which the articles of merchandise are clearly visible. The top of cylindrical housing 5 is closed by a removable cover member 6 having an annular groove 7 therein to fit over the upper peripheral edge of the cylindrical housing 5. The center of the removable cover 6 has a flanged recess 8 therein which supports a sleeve member 9 engageable over the upper end of the vertically extending rotatable shaft 10 which carries the rotatable turret shown generally at 11.

Vertically extending rotatable shaft 10 is journaled in base housing 1 in base bearing 12 and in the bearing 14 carried by horizontally extending bracket 15. The vertically extending rotatable shaft 10 has bevel gear 16 keyed thereto immediately beneath the index plate 17, which is also keyed to vertically extending rotatable shaft 10. The vertically extending rotatable shaft 10 carries a pair of spaced turret spider plates represented at 18 and 19, spaced one from the other with inwardly curved peripheral recesses shown, for example, at 18a, 18b, 18c, 18d, 18e, 18f, 18g, and 18h. It will be understood that the turret spider plate 19 is provided with similar vertically aligned recesses. In these vertically aligned peripheral recesses I mount vertically extending storage chutes which I have represented at 20a, 20b, 20c, 20d, 20e, 20f, 20g and 20h, which open at the side and at the top for receiving the individual cracker sandwiches or packaged groups of cracker sandwiches. The shape of each vertically extending storage chute is such that the cracker sandwich or the packaged groups of cracker sandwiches will be readily retained therein after being readily loaded therein through the removable top 6 of the vending machine. Cracker sandwiches of one kind are loaded in one storage chute, while cracker sandwiches of other kinds are individually loaded in the other storage chutes.

The construction of the storage chutes to properly guide and discharge the individual cracker sandwiches or packaged groups of cracker sandwiches, is one of the novel features of my invention. Inasmuch as the cracker sandwiches are fragile and readily breakable, they must be carefully protected against abrasion. This is accomplished by making each storage chute slightly larger than the plane surface dimension of the cracker sandwich so that the cracker sandwiches may freely gravitate down the storage chutes while being confined therein by reason of the circular section of the chutes terminating adjacent the delivery ends of the chutes. The base of each

storage chute is formed as represented more clearly in Figs. 10, 11, 12, 16 and 17, wherein storage chute 20h is transversely slotted near the base thereof at 20h'. In a similar manner, the other storage chutes are transversely slotted, as also represented in the case of storage chute 20d at 20d', and the side walls thereof extended as shown at 20h'' and 20h'''. In the case of storage chute 20d, I have shown the side wall extension at the base of the storage chute at 20d'''. These side wall extensions are slotted in opposed positions as represented at 21 and 22 in the case of storage chute 20l, and at 23 in the case of storage chute 20d. I provide pairs of spring fingers which extend through these opposed slots, as represented at 24 and 25 in Figs. 1, 3, and 6. These spring fingers are inherently resilient and extend inwardly toward each other, loosely engaging the cracker sandwich or packaged group of cracker sandwiches, represented at 26.

In referring to the single cracker sandwich and the packaged group of cracker sandwiches, I desire that it be understood that the machine of my invention is adapted for vending either a single cracker sandwich or a plurality of cracker sandwiches. This is accomplished by modifying the base structure of each of the storage chutes so as to receive and retain either a single cracker sandwich or a packaged group of cracker sandwiches. In order to render the merchandise of the cracker sandwiches entirely sanitary, the individual cracker sandwiches or the packaged group of cracker sandwiches may be wrapped in a preservative wrapper such as wax paper and the like, and vended upon deposit of a coin in the coin actuating mechanism. There are localities in which a single cracker sandwich vending machine is highly practical where the cracker sandwich must be delivered upon deposit of one cent. Other localities make practical the vending of a packaged group of cracker sandwiches upon deposit of 5 cents. I accordingly shape the base structure of each storage chute to retain a cracker sandwich or a packaged group of cracker sandwiches, the depth of the base structure being varied in each instance.

The base structure of each storage chute is slotted in the rear thereof, as represented at 27 in the case of storage chute 20h, and at 28 in the case of storage chute 20d. Similarly, slots are provided in the base structure of each of the other storage chutes, as will be seen in Fig. 3, at 29 and 30. These slots permit the passage of the ejector member 31 which is pivotally mounted at 32 in the bracket 15 immediately below the bottom ends of the storage chutes on the rotary turret.

Each storage chute has the bottom end thereof closed by a bifurcated member terminating in a pair of outwardly flared discharge portions 33a, 33b, 33c, 33d, 33e, 33f, 33g, and 33h. The ejector member 31 passes through the slot between the bifurcated portions 33a—33h when a slotted storage chute is moved to a position in alignment with the ejector member 31, whereby ejector member 31 is free to move through the rear slot such as 27 in the rear of the storage chute 20h and between the portions of the bifurcated base closure of the storage chute represented at 33h, for ejecting a cracker sandwich or packaged group of cracker sandwiches gravitationally received in the base of the storage chute. The orienting mechanism for selectively moving the vertically disposed rotary turret comprises shaft 34 journalled in bearings mount-

ed in the support 35 and terminating in bevel gear 36 which meshes with bevel gear 16 on the vertically arranged shaft 10. The shaft 34 has an actuating knob 37 on the end thereof which projects through the front wall of the base housing 1. Shaft 34 carries a calibrated dial 38 thereon which coacts with a fixed reference indicator 39 carried by the front wall of base housing 1 represented at 39, designating the positions to which the rotary turret must be moved in aligning a particular storage chute 20a—20h with the ejector member 31. This alignment is accomplished by the coaction of index plate 17 with the pawl mechanism shown generally at 40. The pawl mechanism includes a standard 41 which is mounted upon plate 42 mounted on support 35. Standard 41 carries a pivotally mounted crossarm 43 journaled thereon at 44. One end of said crossarm 43 carries pawl 45 thereon having a vertically extending stop member 46 projecting vertically therefrom. Stop member 46 provides an abutment means for preventing movement of the coin mechanism bar 47 when pawl 45 is raised out of engagement with one of the grooves on the index plate 17.

The index plate 17 is provided with a plurality of radially disposed V-shaped grooves extending partially through the radial dimension of the index plate 17 from the periphery thereof toward the center. These grooves extend partially into the upper surface of the index plate 17, as represented at 48a, 48b, 48c, 48d, 48e, 48f, 48g, and 48h. Pawl 45 is adapted to enter the recesses constituted by the grooves 48a—48h, and when so positioned the stop 46 clears the coin mechanism bar 47 allowing the coin mechanism bar to move horizontally for actuating the ejector member 31.

The pawl mechanism 40 also includes a compression spring member 49 disposed between standard 41 and the opposite end of the pivotally mounted crossarm 43, tending to force crossarm 43 to a position in which pawl 45 seeks to enter the recesses formed by grooves 48a—48h or to ride on the surface of index plate 17 intermediate the said recesses. When the pawl 45 enters in one of the recesses 48a—48h, stop 46 falls below the horizontal path of movement of the coin mechanism bar 47 so that the coin mechanism may be actuated. For all positions in which pawl 45 rides on the top surface of index plate 17, stop 46 forms an obstruction in the path of movement of the coin mechanism bar 47, preventing operation of the coin actuating mechanism.

The coin actuating mechanism is represented at 50 projecting beyond the front of the base housing 1 for receiving coins of the denomination intended for operating the coin actuating mechanism. The coin operating mechanism is of conventional construction and is represented at 51 mounted interiorly of the base housing 1 and above the pawl mechanism 40 mounted on standard 41. The coin mechanism bar 47 carries an actuating member 52 which is in the form of a vertically extending finger member operative to engage the downwardly depending curved end 31a of ejector member 31. The downwardly depending end 31a of ejector member 31 has a curved recess 31b with respect to which the finger member 52 establishes sliding contact when a coin is inserted and bar 47 pushed rearwardly through the medium of the inserted coin. The translatory movement of the finger member 52 is converted into angular movement of ejector

member 31 as the finger member 52 rides against the curved recess 31b of the depending end 31a of ejector member 31. As the finger member 52 advances against the depending end 31a of ejector member 31 a movement through an arc of something less than 90° is performed by ejector member 31. The upper end of ejector member 31 is flat with the forward edge thereof formed in a compound curve 31c which is approximately sinusoidal in contour, enabling a progressive engagement of the edge of the cracker sandwich or packaged group of cracker sandwiches as ejector member 31 passes through slot 21, for example, in the rear of storage chute 20h, for progressively forcing the individual cracker sandwich or packaged group of cracker sandwiches out of retaining engagement by spring arms 24 and 25 (in the case of chute 20h). The curve 31b on the depending end of ejector member 31 coacting with finger member 52 is directly related to the compound curve on the edge 31c of the upper projecting end of ejector member 31 to effect a release of the spring retained cracker sandwich or packaged group of cracker sandwiches in the end of the storage chutes.

I provide a funnel-shaped guide for receiving the individual cracker sandwiches or packaged group of cracker sandwiches as they are detached from the ends of the storage chutes as represented at 53, through which the cracker sandwich or packaged group of cracker sandwiches are guided to the delivery chute represented at 54 at the front of the base housing 1.

The selector mechanism operated by actuating knob 37 is controlled from the front of the vending machine by revolving actuating knob 37 to move the calibrated dial 38 thereon with respect to the fixed reference indicator 39 on the front of the base housing 1 to move the rotatable turret 11 to a selected position.

The chutes 20a—20h each carry large designating numerals, represented for example as 1-8 clearly visible through the transparent cylindrical housing 5. A card carrier 55 shown in Figs. 18 and 19 attached to the front of housing 1 supports a card 56 on which there is displayed the kind of sandwiches stored in each of the chutes, such as

1. Peanut Butter	6. Raisin Cracker
2. Cheese Cracker	7. Whole Wheat Peanut
3. Fig Newton	Butter
4. Cream Vanilla	8. Rye Peanut Butter
5. Cream Chocolate	

Shaft 34, which is revolved by actuating knob 37, moves bevel gears 36 and 16 for revolving the vertically rotatably disposed shaft 10. Starting from a position of rest in which pawl 45, by virtue of compression spring 49, occupies a position within any one of the grooved recesses 48a—48h in index plate 17, it is necessary to apply sufficient torque to actuating knob 37 to raise pawl 45 out of the grooved recess. In doing this the stop 46 is shifted vertically with pawl 45 riding on the top surface of index plate 17 intermediate two radially disposed grooves therein, which disables the movement of coin mechanism bar 47 because stop 46 moves into the horizontal path of movement thereof and finger member 52 cannot contact the curved face 31b of the depending end 31a of the ejector member 31. Accordingly, ejector member 31 remains in the position illustrated in Fig. 7, in which the upper end 31c thereof rests against the supporting stop 68 of the bracket

15 being spring urged to that position by spring 69. The open side of each of the storage chutes extends radially outward so that the contents of each storage chute are readily observable by the customer looking through transparent housing 5. With the upper end 31c of the ejector member 31 resting in the space between the rear of the storage chutes and the shaft 10, the turret may be revolved under control of actuating knob 31 to bring the selected storage chute in line with the front of the vending machine. The customer thus selects the storage chute which contains the cracker sandwiches of the kind desired. As pawl 45 drops into the coacting recessed groove in index plate 17 and stop 46 moves clear of the coin mechanism bar 47 enabling a coin to be inserted in the coin chute at 50 for imparting horizontal movement to the coin mechanism bar 47 and correspondingly moving finger 52. As heretofore explained, finger 52 engages the curved edge 31b of the ejector member 31, moving ejector member 31 in a curved path by which the curved face 31c engages the inner edge of the cracker sandwich or the packaged group of cracker sandwiches, and effects a release thereof from the retaining springs 24 and 25. Delivery of each cracker sandwich or packaged group of cracker sandwiches is then effected through guide 53 and chute 54. As each cracker sandwich or packaged group of cracker sandwiches is released from the base storage chutes, a replacement cracker sandwich or packaged group of cracker sandwiches gravitationally drops into the base of the storage chute and is retained therein by the spring members 24 and 25 preparatory to the next succeeding ejection operation.

As heretofore explained, the cover 6 and the housing 5 are readily removable to facilitate repair, cleaning, and reloading of the machine. Only slight modification is required in each machine to change the delivery characteristics from a single cracker sandwich vending device to a vending device for packaged group of cracker sandwiches. This is accomplished by changing the depth of the base portion below the slotted portion 20h or 20d of each storage chute.

In Figs. 13-15 I have shown a modified form of index mechanism wherein a drum 57 is mounted on shaft 10 in lieu of index plate 17. The drum 57 has a multiplicity of vertically extending slots 58a, 58b, 58c, 58d, 58e, 58f, 58g and 58h in the cylindrical wall thereof which serve as passages for the coin mechanism bar 47 when the slots are properly oriented slots and are aligned in conformity with the positions of the storage chutes in a manner similar to the operation of index plate 17. The intermediate curved wall portions of the drum 57 serve as abutments for preventing operation of coin mechanism bar 47 in all positions of the turret where the storage delivery chutes are not properly aligned with the discharge mechanism. The underside of the base of the drum 57 extends horizontally and is provided with aligned recesses 59a, 59b, 59c, 59d, 59e, 59f, 59g and 59h into which the pawl 60 is continuously urged by spring 61 mounted in socket 62 carried by the support 35. Movement of shaft 34 therefore effects a shifting of drum 57 to positions which may be maintained by the latching of pawl 60 in a selected release aligned with the respective storage chutes, at which time the coin mechanism bar 47 may be operated for effecting discharge of an article of merchandise. Until the drum 57 is moved to a proper position permitting passage of the coin mechanism bar

47 through an aligned slot the merchandise feed mechanism is blocked from operation as heretofore explained.

As heretofore explained, the structure of my invention is particularly adapted for conversion from the feeding of packaged articles of substantial thickness or depth to packaged articles of smaller thickness or depth. This is accomplished in a very simple manner as illustrated particularly in Figs. 16 and 17, wherein the base of the storage chute, represented for example at 20h, is filled by an inserted member 63 which conforms with the interior of the base of the storage chute. The inserted member 63 has a pair of ears 63a and 63b which fit within the rear wall slot 27 in the storage chute for retaining the filler member 63 in position. The depth of the filler member 63 is such that only a single cracker sandwich, represented at 64, is exposed to the path of travel of ejector member 31, while succeeding single cracker sandwiches indicated at 65 and 66 are retained in the storage chute 20h in a position above the path of the ejector member 31. The single cracker sandwich 64 in dropping to the bottom of the storage chute 20h is restrained against ejection by spring fingers 24 in a manner similar to the restraint of the larger size package as explained in Figs. 7-12.

The ejection mechanism is the same whether the merchandise article be a single cracker sandwich or a multiple cracker sandwich as the ejector member 31 merely engages the packages of different depths at different positions along the forward edge 31c. The rearward edge 31d of the ejector arm forms an abutment with the inclined stop 68 on bracket 15. A tension coil spring 69 interconnects ejector arm 31 with bracket 15 and tends to normally maintain the ejector arm 31 in the rear of the storage chute, as represented in Fig. 7 at 20h, with the abutment edge 31d of ejector arm 31 resting against stop 68. When, however, the coin mechanism bar 47 is released by the insertion of a coin, ejector arm 31 is moved about an orbit centered about axis 32 as shown in Fig. 8 which continues as illustrated in Fig. 9 as the coin mechanism bar 47 is pressed further inwardly with finger member 52 in contacting relation with the curved edge 31b of the ejector arm to the position illustrated in Fig. 9 where the merchandise 26 is ejected and discharged from the lower end of the storage chute, the ejector arm 31 passing through slot 27. Tension coil spring 69 by this time has stretched to an expanded position, but rapidly contracts when finger member 52 is withdrawn, restoring ejector arm 31 to the position shown in Fig. 7, ready for the succeeding ejection operation with the coin mechanism bar 47 being restored by spring mechanism associated with the coin actuating mechanism 50.

The inserted member 63 has an inclined discharge face 67 thereon facilitating the discharge of each single cracker sandwich as represented in dotted line position 68 in the course of its passage into the delivery chute 54.

The conversion of the machine from delivery of a large size article to the smaller size article responsive to insertion of a coin of smaller denomination is very simple and may be accomplished rapidly.

In illustrating my invention as adapted for delivering cracker sandwiches of round contour, I desire that the structure be considered in the illustrating sense and not in the limiting sense, for obviously cracker sandwiches of square or

any other contour may be readily vended by modifying the shapes of the storage chutes to receive the cracker sandwiches of such modified contour.

Throughout the claims I have referred to the vending machine of my invention as operating upon articles of merchandise generally, for I realize that although I have designed the machine of my invention specifically for the vending of cracker sandwiches, that other articles of merchandise may be vended by the same mechanism as I have shown herein. Moreover, I realize that other modifications in the construction and arrangement of parts of the mechanism of my invention may be made, and while I have described my invention in one of its preferred embodiments I desire that it be understood that no limitations upon my invention are intended other than may be imposed by the scope of the appended claims.

What I claim as new and desire to secure by Letters Patent of the United States is as follows:

1. In a vending machine a frame, a vertically disposed shaft, a rotary turret carried by said shaft and including a multiplicity of vertically arranged storage chutes for gravitationally guiding articles of merchandise therethrough, each of said storage chutes terminating in a discharge base portion, an ejector pivotally mounted with respect to said frame in such a manner that pivotal action will cause an article to be ejected from the discharge base portion of a selected chute, an index plate carried by said vertically disposed shaft, said index plate having a multiplicity of radially extending grooves therein, a pivotally mounted pawl mechanism including a detent having an upwardly extending abutment stop thereon, spring means for continuously urging said detent into engagement with said index plate for positioning either of two planes, one determined by engagement of said detent with the surface of said index plate and the other determined by the engagement of said detent within said grooves, and a coin actuated slide aligned in the path of the pivoted ejector, said slide being blocked from movement by the upwardly extending abutment stop when said stop is in the position determined by engagement of the detent with the surface of the index plate, but said slide being adapted to clear said stop and actuate the ejector when the detent is in the other of its two positions, and means to impart rotation to the vertically disposed shaft.

2. A vending machine as set forth in claim 1 in which the grooves in said index plate are aligned with said storage chutes whereby said detent enters a selected groove when the groove aligned with a storage chute is moved to discharge position, whereby said coin actuated slide is operative only at the time that a storage chute is in discharge position.

3. A vending machine as set forth in claim 1 in which said last named means includes a manually controlled gear mechanism whereby said turret may be rotated to a selected discharge position prior to operation of said coin actuated slide.

4. A vending machine as set forth in claim 1 in which the grooves in said index plate are aligned with said storage chutes and wherein said detent enters a selected groove when the groove aligned with a storage chute is moved to discharge position and in which gear mechanism is associated with said shaft and a manually operated shaft for controlling said gear mechanism for movement of said turret to selected positions for alternately shifting the detent of said pawl mechanism to positions in which said abutment

stop blocks or unblocks said coin actuating slide for allowing operation of said coin actuated slide only when a selected storage chute is aligned in the discharge position thereof.

5. A vending machine as set forth in claim 1 in which the grooves in said index plate are aligned with said storage chutes and wherein said detent enters a selected groove when the groove aligned with a storage chute is moved to discharge
10. position and in which said coin actuated slide is located above said detent and in which a gear mechanism is associated with said shaft and wherein said shaft is manually controllable for operating said gear mechanism, for moving said
15. turret and displacing said detent downwardly to a position in which the abutment stop thereon clears said coin actuated slide for permitting operation of said coin actuated slide only when a selected storage chute is in discharge position.

20 6. A vending machine comprising a vertically disposed shaft, a rotatable turret carried by said shaft, a multiplicity of vertically extending storage chutes mounted on said turret with the sides of said storage chutes opening externally with
25 respect to said turret, each storage chute terminating in a base portion bifurcated at its inner side and end, with a discharge opening extending radially outwardly from the base thereof, a filler insert for the end of the base portion of said storage chute for positioning the merchandise package to be vended in a position adapted to be ejected from said chute, said filler insert having a slot therein aligned with the bifurcated portion of the inner side and end of the chute, and an
30 35 ejector member pivotally mounted below the bifurcated end of said storage chute and means for imparting movement to said ejector member whereby said ejector member moves through the bifurcated side and bottom of a selected storage
40 chute and through the slot in said filler insert for ejecting an article of merchandise gravitationally movable down the storage chute, through the side thereof.

7. A vending machine comprising a vertically disposed shaft, a rotatable turret carried by said shaft, a multiplicity of vertically extending storage chutes mounted on said turret with the sides of said storage chutes opening externally with respect to said turret, each storage chute terminating in a base portion bifurcated at its inner side and end, with a discharge opening extending radially outwardly from the base thereof, a filler insert for the end of the base portion of said storage chute for positioning the merchandise package to be vended in a position adapted to be ejected from said chute, said filler insert having a slot therein aligned with the bifurcated portion of the inner side and end of the chute, an ejector member pivotally mounted below the bifurcated end of said storage chute, means for imparting movement to said ejector member whereby said ejector member moves through the bifurcated side and bottom of a selected storage chute and through the slot in said filler insert for ejecting an article of merchandise gravitationally movable down the storage chute, through the side thereof, and means on said filler insert extending through the bifurcated inner side of said storage chute for maintaining said filler insert in position in said storage chute while said ejector member operates therein.

8. A vending machine comprising a vertically disposed shaft, a rotatable turret carried by said shaft, a multiplicity of vertically extending storage chutes mounted on said turret with the sides

of said storage chutes opening externally with respect to said turret, each storage chute terminating in a base portion bifurcated at its inner side and end, with a discharge opening extending radially outwardly from the base thereof; a filler insert for the end of the base portion of said storage chute for positioning the merchandise package to be vended in a position adapted to be ejected from said chute, said filler insert having a slot therein aligned with the bifurcated portion of the inner side and end of the chute, an ejector member pivotally mounted below the bifurcated end of said storage chute, means for imparting movement to said ejector member whereby said ejector member moves through the bifurcated side and bottom of a selected storage chute and through the slot in said filler insert for ejecting an article of merchandise gravitationally movable down the storage chute, through the side thereof, and a pair of ears extending from said filler insert and through the bifurcated inner side of said storage chute and engaging the outside wall thereof for maintaining said filler insert in position in said storage chute while said ejector member operates therein.

9. A vending machine comprising a vertically disposed shaft, a rotatable turret carried by said shaft, a multiplicity of vertically extending storage chutes mounted on said turret with the sides of said storage chutes opening externally with respect to said turret, each storage chute terminating in a base portion bifurcated at its inner side and end, with a discharge opening extending

radially outwardly from the base thereof, a filler insert for the end of the base portion of said storage chute for positioning the merchandise package to be vended in a position adapted to be ejected from said chute, said filler insert having a slot therein aligned with the bifurcated portion of the inner side and end of the chute, and the top surface of said filler insert being disposed in a plane inclined downwardly toward the discharge opening in the chute, an ejector member pivotally mounted below the bifurcated end of said storage chute, and means for imparting movement to said ejector member whereby said ejector member moves through the bifurcated side and bottom of a selected storage chute and through the slot in said filler insert for ejecting an article of merchandise gravitationally movable down the storage chute, through the side thereof, down the inclined plane forming the top of said filler insert.

WILLIAM CLARK MAKIBBIN.
